UNITED STATES PATENT OFFICE.

GEORGE W. SCHODDE, OF NEW YORK, N. Y., ASSIGNOR, BY MESNE ASSIGNMENTS, TO
MILTON SCHNAIER, OF NEW YORK, N. Y.

CESSPOOL.

988,667.

Specification of Letters Patent.

Patented Apr. 4, 1911.

Application filed July 31, 1907. Serial No. 386,354.

To all whom it may concern:

Be it known that I, GEORGE W. SCHODDE, a citizen of the United States, residing at the city of New York, borough of Manhattan, in the county and State of New York, have invented certain new and useful Improvements in Cesspools, of which the following is a full, clear, and exact specification.

10 My invention relates to improvements in plumbing, and the same has for its object more particularly to provide a cesspool which may be readily adjusted and secured in position in reinforced concrete floors or 15 structures.

Further said invention has for its object to provide a cesspool to which a flashing of any desirable shape and size may be readily applied in order to arrest any fluid matter 20 which may pass between the outer surface of said cesspool and the flooring in which it is secured.

Further said invention has for its object to provide a cesspool which may be securely 25 anchored to the flooring in which it is supported.

To the attainment of the aforesaid objects and ends my invention consists in the novel 30 details of construction, and in the combination, connection and arrangement of parts hereinafter more fully described and then pointed out in the claims.

In the accompanying drawings wherein like numerals of reference indicate like 35 parts, Figure 1 is a central section, taken at about the line 1—1 of Fig. 2, and illustrates one form of a cesspool made according to and embodying my said invention, and, Fig. 2 is a plan or top view, partly broken away; 40 and in section on about the line 2—2 of Fig. 1.

In said drawings 10 designates the cesspool which is composed essentially of a circular receptacle portion 11, and a coupling sleeve member 12 secured to the base thereof. At the upper edge of said circular receptacle 11 is provided a lateral flange 13, which is rectangular in outline, and at the junction of its inner edge with the upper 50 edge of said receptacle is provided an annular recess 14 adapted to receive a perforated circular cover plate 15. The base of said receptacle 11 is provided with an aperture, and a horizontal inwardly projecting flange 16. 55 The sleeve member 12 is provided at its

lower edge with an inwardly projecting flange 17, and within said sleeve member is disposed one end of a waste pipe 18 which is secured therein by a packing 19 of oakum, and calked with lead 20. Upon the outer 60 surface of said sleeve member 12 adjacent to its upper edge is an outwardly projecting flange or shoulder 21 which conforms substantially to the inwardly projecting flange 16 of the receptacle 11.

22 denotes a flashing made preferably of sheet lead or analogous material capable of being bent or shaped. This flashing may be of any desired shape and size, but in order to insure more perfect results, it is by preference made larger in outline than the upper portion of the receptacle 11 and its flange 13. The flashing 22 is provided at its center with an aperture to receive the upper end of the sleeve member 12 and is secured to the 70 cesspool intermediate the flange 16 of the receptacle, and the flange 21 of the sleeve member 12 by screws 23, 23 which extend through the flange 16, the flashing 22, and into the flange 21 of said sleeve member 12.

Upon the outer surface of the sleeve member 12 directly below the flange 21 thereof is disposed the means for supporting and anchoring the cesspool in position in the flooring, and is here shown consisting of four 85 rods or arms 24, 24 which may be either round in cross-section as shown or square and twisted in order to insure firmer anchoring. The said rods or arms 24, 24 are arranged in pairs, one rod at each side of the sleeve member 12, and the others similarly arranged but at right angles to the first mentioned pair as shown at Fig. 2. The ends of said rods or arms are thereupon twisted at 90 25, 25, and their projecting ends permitted 95 to rest upon the longitudinal and transverse reinforcing rods 26, 26 embedded in the concrete work 27 of the floor.

It will be apparent that while the flashing 22 may be made of any suitable material, I prefer to make the same of some flexible substance, such as sheet lead as that permits of the flashing being made either flat as shown in full lines at Fig. 2 or dished to form a receptacle, and thereby 100 effectually prevent any fluid matter which may find its way down upon the outer surface of the receptacle 11 getting by said flashing and leaking to the floor below.

Having thus described my invention, what 110

I claim and desire to secure by Letters Patent is:

1. A cesspool comprising a receptacle divided horizontally to form a lower section, 5 and an upper section supported upon said lower portion, a flashing interposed between said sections and extending outwardly therefrom, and means for securing said sections and flashing together, substantially as 10 specified.
  2. A cesspool comprising a receptacle consisting of a flanged lower section, and an upper section supported upon said flanged lower section, a flashing interposed between 15 said flanged lower section and said upper section, and means for securing said upper section to said lower section and said flashing in position there-between, substantially as 20 specified.
  3. A cesspool comprising a receptacle consisting of a lower section, a flange along the upper edge thereof, an upper section mounted upon said lower section, a flashing interposed between the base of said upper 25 section and the flange of said lower section, and means for securing said upper section to the flange on said lower section and said flashing in position there-between, substantially as 30 specified.
  4. A cesspool comprising a receptacle consisting of a lower section, an outwardly-extending flange along the upper edge of said lower section, an upper section relatively larger than said lower section 35 mounted thereon, a flashing disposed intermediate the base of said upper section and the flange of said lower section, and securing means extending through the base of said upper section and said flashing and engaging the flange of said lower section for securing said receptacle sections and flashing together, substantially as 40 specified.
  5. A cesspool comprising a receptacle, a flange at its base, a sleeve member provided 45 at its upper edge with a flange, a flashing disposed intermediate said flanges and means for securing the flanged edges of said receptacle and sleeve member and the flashing therebetween together, substantially as 50 specified.
  6. A cesspool comprising a receptacle, a flanged aperture at its base, a sleeve member adapted to enter said aperture and provided with a flange, a flashing disposed 55 upon said sleeve intermediate the flange thereof and the base of said receptacle, and means for securing said receptacle together, substantially as specified.
  7. A cesspool comprising a receptacle, a flange at its base, a sleeve member provided 60
- at its upper edge with a flange, a flexible flashing disposed intermediate said flanges, and means for securing the flanged edges of said receptacle and sleeve member and the flashing therebetween together, substantially as 65 specified.
8. A cesspool comprising a receptacle having an aperture at its base, and an inwardly projecting flange, a sleeve member adapted to enter said flanged recess, a flange 70 upon the outer surface of said sleeve member adjacent to its upper end, a flashing disposed upon the upper flanged end of said sleeve member and projecting outwardly therefrom, and means for securing said receptacle, sleeve member and flashing together, substantially as 75 specified.
9. A cesspool comprising a receptacle, a sleeve member thereon, and supporting members secured thereto for supporting 80 said cesspool, substantially as specified.
10. A cesspool comprising a receptacle, a sleeve member thereon, and a plurality of members extending laterally therefrom for supporting said cesspool, substantially as 85 specified.
11. A cesspool comprising a receptacle, a sleeve member thereon, a shoulder on said sleeve member, and a plurality of members secured to said sleeve member below said 90 shoulder for supporting said cesspool, substantially as specified.
12. A cesspool comprising a receptacle, a sleeve member thereon, and a plurality of rods secured together and to said sleeve 95 member for supporting said cesspool, substantially as specified.
13. A cesspool comprising a receptacle, a sleeve member thereon, a shoulder on said sleeve member, and a plurality of rods secured together upon said sleeve member below the shoulder thereon, and having their ends extending laterally therefrom for supporting said cesspool, substantially as specified. 100
14. A cesspool comprising a receptacle, a sleeve member adapted for securement thereto, a flashing secured thereto intermediate said receptacle and sleeve member, and a plurality of flexible arms secured together and to said sleeve member, substantially as specified. 105

Signed at the city of New York, in the county and State of New York, this 21st day of March, nineteen hundred and seven. 115
